SAFETY HELMET

Eitaro Kamata, Tokyo, Japan, assignor to American Safety Equipment Corporation, Sherman Oaks, Calif., a corporation of New York

Filed Nov. 12, 1968, Ser. No. 14,412

Term of patent 14 years

Int. Cl. D2—03

U.S. Cl. D2—231

FIG. 1

FIG. 2

FIG. 3

FIG. 4

FIG. 5

FIG. 1 is a side elevational view of a safety helmet showing my new design, the side opposite being a mirror image thereof;

FIG. 2 is a front, elevational view thereof.

FIG. 3 is a rear, elevational view thereof.

FIG. 4 is an enlarged cross-sectional view taken on line 4—4 of FIG. 1.

FIG. 5 is an enlarged cross-sectional view taken on line 5—5 of FIG. 1.

I claim:

The ornamental design for a safety helmet, as shown and described.
